UNITED STATES PATENT OFFICE

AXEL G. J. RAPP, OF CHICAGO, ILLINOIS, ASSIGNEE TO LINK-BELT COMPANY, OF CHICAGO, ILLINOIS, A CORPORATION OF ILLINOIS.

SETTLING-TANK.

1,137,351.

Specification of Letters Patent.

Patented Apr. 27, 1915.

Application filed October 26, 1914. Serial No. 868,563.

To all whom it may concern:

Be it known that I, AXEL G. J. RAPP, a citizen of the United States, residing at Chicago, in the county of Cook and State 5 of Illinois, have invented a certain new and useful Improvement in Settling-Tanks, of which the following is a specification.

My invention relates, generally speaking, to improvements in settling tanks and has 10 for one object to provide a new and improved means for separating out or withdrawing the sand from the water in the settling tank, particularly in connection with the fine silt in gravel washing.

My invention is illustrated more or less 15 diagrammatically in one form in the accompanying drawing wherein—

Figure 1 is a vertical section through my 20 device. Fig. 2 is a side elevation viewed in the direction of the arrow in Fig. 1.

A, A is a main supporting frame, A¹ is a 25 settling tank; it may be pyramidal or conical or any other suitable shape, provided, as indicated, the bottom is materially smaller than the top and the bottom and side walls are rapidly sloping to permit 30 material to slide down toward the center. This tank is supported at one side by means of a bearing A², being held free to rotate 35 about that bearing. It is supported at the other side by a knife edge A³, resting on a lever A⁴. This lever has a fulcrum A⁵ and is counterbalanced by an adjustable weight A⁶. There is an opening B at the bottom of 40 the tank closed by any suitable door such as the conical plug B¹. This plug is suspended by a stem B² guided at B³ and supported on the end of the lever A⁴.

C is a chute through which water bearing 45 sand or other particles in suspension is allowed to flow into the tank.

C¹ is an overflow tank or trap for the water arranged beneath the edge of the tank into which the overflow water is guided 45 by the veins C² on the tank.

D is a sand receptacle located beneath the tank to receive the material discharged through the bottom opening when the plug or door is open.

It will be evident that while I have shown 50 in my drawing an operative device, still many changes might be made in the size, shape and arrangement of parts without departing materially from the spirit of my

invention. I wish, therefore, that my drawing be taken as in a sense diagrammatic.

The use and operation of my invention are as follows:—The water bearing the fine particles in suspension is permitted to flow into the tank, filling it and gradually overflowing and running off around the edge. The water being more or less at rest in the tank, the fine material in suspension settles to the bottom and will fill the tank to a certain level. This material being heavier than the water adds to the weight of the tank until finally it has sufficiently counterbalanced the weight on the end of the supporting lever and the tank descends, slightly tipping the lever. However, since the tank is supported on the lever adjacent the fulcrum and the plug or valve is supported on the lever at a point far removed from the fulcrum, the valve will go down more rapidly than the tank and therefore the valve will be open and the sand will rush out through the opening at the bottom until enough has gone to permit the weight to draw the tank back up to its normal filling position. This process continues as long as water containing sand or other fine particles is fed to the tank.

I claim:

1. A settling tank pivoted at one side, a scale beam supporting the opposed side, an extension on the scale beam projecting over the tank the bottom of the tank being apertured for discharge, a valve controlling said aperture and a connection from the scale beam extension to said valve said connection passing up through the tank, the tank and valve rod being each connected to the beam on the same side of its fulcrum, the latter being farther from the fulcrum than the tank connection.

2. A settling tank pivoted at one side supported at the other side by a weighing mechanism, having a discharge port at the bottom thereof and a valve mounted for vertical movement to and from said port to control it; a valve stem projecting upward from said port through the said tank and an extension from the weighing means overhanging the tank and supporting said valve stem, the tank and valve rod being each connected to the beam on the same side of its fulcrum, the latter being farther from the fulcrum than the tank connection.

3. A settling tank pivotally mounted on one side a scale beam, a connection between the scale beam and the tank and an extension projecting from said scale beam on the side removed from the fulcrum of the beam and overhanging the tank and a valve stem passing up through the tank and suspended on said extension, the tank and valve rod being each connected to the beam on the same side of its fulcrum, the latter being farther from the fulcrum than the tank connection.

4. A settling tank pivoted to one side, a scale beam supporting the opposed side, a discharge valve on the bottom of the tank.

and means for moving the valve and the tank in the same direction at different velocities, said means comprising an extension projecting from the scale beam beyond its point of connection with the tank and overhanging the tank and a connection from it to the valve. 20

In testimony whereof, I affix my signature in the presence of two witnesses this 22 day of October 1914.

AXEL G. J. RAPP.
